UNITED STATES PATENT OFFICE.

WILLIAM H. FORD, OF LOWELL, MASSACHUSETTS, ASSIGNOR OF ONE-HALF TO FRANK HANCHETT, OF LOWELL, MASSACHUSETTS.

CORE-MAKING MACHINE.

1,175,740.

Specification of Letters Patent. Patented Mar. 14, 1916.

Application filed September 16, 1913. Serial No. 790,017.

To all whom it may concern:

Be it known that I, WILLIAM H. FORD, a citizen of the United States, and resident of Lowell, county of Middlesex, State of Massachusetts, have invented an Improvement in Core-Making Machines, of which the following description, in connection with the accompanying drawings, is a specification, like letters on the drawings representing like parts.

My present invention is a core making machine for use particularly in the manufacture of jewelry, where a specially strong, accurate and adjustable machine is necessary.

The object of the invention is to provide a core making machine which will have provision for making cores of any size, depth, thickness or contour and which will be readily adjustable for such cores of varying form and thickness, and furthermore to produce a machine which will have mechanism to remove, quickly, a core when made and to be ready for a successive core, thus greatly expediting this operation.

To this end I form a machine having a core holder which may be interchanged at will and which also may be quickly adjusted with great exactness and when so adjusted may be locked in position to determine the depth and extent of the core to be made. In my inventions for making rings by casting the seal, signet, emblem, monogram, or the like, which heretofore would be engraved, or for casting the ring with a bezel of any size or form, it is necessary to make such cores with great delicacy and exactness and the machine illustrated herein is intended primarily for use in making such cores, although it is not, of course, limited to such use.

Other features of the invention, novel combination of parts, and details of construction, will be hereinafter more fully pointed out and claimed.

In the drawings, Figure 1 illustrates a preferred embodiment of the invention with a portion of the base broken away, Fig. 2 is a view partly in section, at right angles to that shown in Fig. 1, Fig. 3 is a plan

view; Fig. 4 is a detail cross sectional view showing the die molding material when the core is completed before being removed; and Fig. 5 is a plan view of the die support.

It will be readily understood that a core making machine must be of comparatively heavy and rigid workmanship in order properly to withstand the operations of pounding, hammering, and forcing the mold material into the core cavity and upon the die plate, if one is used, to reproduce the delicate impression thereof, especially when such die plate carries engraved insignia. My machine is made preferably of metal, and comprises a base 1 and a column 2 supported on said base and secured thereto in any suitable manner, as by screws 3 and 4. The column 2 is bored centrally, as indicated at 5 and is formed with an open recess 6, which recess is closed by the base plate 1. The upper portion of the column 2 is reduced in diameter at 7, and is threaded to receive the correspondingly threaded portion 8 of an upper and adjustable column 9 (see Fig. 2) which member 9 is also bored axially as indicated at 10. On the reduced portion 7 of the column 2 is threaded a clamping nut 11, which acts to lock the upper column 9 in its position on the column 2, so as to secure these two columns in any relative position desired. This arrangement permits an adjustment for height to be made, and consequently depth of the core, as will be explained. The upper portion of the column 9 is threaded as indicated at 12, to carry a core box 13 having coöperating threads to fit on said threaded portion 12 and a shoulder 14 to enable the core box 13 to be firmly and rigidly fitted on top of the column 9, as well as to relieve the threads 12 from strain in forcing the mold material into the core box.

The interior 15 of the core box 13 may be of any desired form, such as round, oval, octagonal, etc., to fit the work in hand, and a plurality of core boxes 13 having such varying diameters, and all adapted to fit on the threads 12 of the machine, will ordinarily be kept on hand and intended to be interchanged as the requirements of the particu-

lar work in hand may demand. In the interior of the core box is a plate or support 16 of similar contour and size for the particular core box to be used therewith. This support or plate 16 is mounted on a rod 17, which extends through the bores 10 and 5 of the supporting columns 9 and 2 into the open space 6 in the base of the machine. In this space the end of the rod 17 rests upon a cam 18, which is supported rigidly on a shaft 19 extending through suitable bearings 20 and 21 at diametrically opposite points in the base 2.

One end portion of the shaft 19 is grooved 15 at 22 to receive a locking nut 23 to hold the shaft in position with the cam 18 directly under the axial bore 5 and therefore under the rod 17. To one end of the shaft 19 is affixed a handle 24. The cam 18 is formed 20 with a straight cam surface 25 and a curved cam face 26, so that as the handle 24 is actuated and the shaft 19 rotated, the cam face 26 will raise or lower the rod 17. With the straight cam face 25 in position under the 25 end of the rod 17, however, a straight firm support is supplied to the shaft 17, and consequently to the plate 16 in the core box 13. The cam 18 is so proportioned that the rod 17 is at its lowermost limit of movement, 30 and hence the plate 16 at its lowermost position in the core box 13, when the straight face 25 is in contact with said rod 17, and when the handle 24 is turned and the curved face 26 of the cam is forced against the rod 17, the rod will be raised to force the plate 16 upwardly to a position substantially flush 35 with the top of the core box 13 so that the core may be readily removed by hand. With the straight face of the cam 25 in contact 40 with the rod 17, said rod and plate 16 will give a solid support to receive the mold material 27, and the core is formed. The provision for relative adjustment as to height of the column 9 to the column 2 enables me 45 to secure a quick adjustment for the depth of the core 27, being made in the core box 13, the two columns 9 and 2 being locked when in desired position by the nut 11. Where a change is desired to be made from oval 50 cores, for example, to square round or octagonal formed cores, one core box 13 is removed, the plate 16 and its rod 17, preferably integral therewith, is also removed and a corresponding plate 16 and core box 13 55 for making a square core is positioned and the core making operation will proceed as before. When the core is completed, the operator actuates the handle 24 to raise the completed core above the level of the top 60 of the core box and remove it. A return of the handle 24 to former position is all that is necessary to have the machine ready for making successive cores.

Where it is desired to make a core with an insignia, a die plate 28 is employed, 65 which will be of corresponding contour to fit the particular interior 15 of the core box 13 being used, similar to the contour of the plate 16 and the columns 9 and 2 may be adjusted relative to each other, so as to prevent the die plate 28 being raised above the level of the top of the core box 12, when the core is lifted, so that said die plate will not be accidentally removed with a core. The operation of the machine with a die plate 70 thereon is similar to that already described when making a plain core. In order to facilitate the adjustment of the columns 2 and 9 relatively to each other, to provide for the extent of the core 27 being made, I prefer to have the lock nut 11 carry a scale 29, which with a fixed mark or guide 30 on the column 2 will enable the operator to determine the height of the core cavity 15, when 75 the machine is locked in position and ready for use.

The advantages of my improved machine will be readily appreciated, enabling cores to be made with great exactness and uniformity and the machine is particularly advantageous in carrying out the invention of my said copending application.

Having described my invention, what I claim as new and desire to secure by Letters Patent is:

1. A core making machine, comprising a supporting standard in the form of a column having its upper portion exteriorly threaded, a core box threaded on to said column and means to hold the same in adjusted position, in combination with a movable die plate carried in said core box, and means to eject said die plate therefrom.

2. A core making machine, comprising a supporting standard in the form of a column having its upper portion exteriorly threaded, a core box threaded on to said column and means to hold the same in adjusted position, in combination with a die plate movably supported in said core box, and means carried by said base to eject the die plate therefrom.

3. A core making machine, comprising a supporting standard in the form of a column having its upper portion exteriorly threaded, a core box threaded on to said column and means to hold the same in adjusted position, and a movable die plate held by a support from the base, whereby adjustment of the core box on the base regulates the depth of the core box.

4. A core making machine, comprising a supporting base and standard in the form of a column having its upper portion exteriorly threaded, a core box, a core box support threaded on to said column and means to

hold the same in adjusted position, both said base and said support being centrally bored to receive a rod, a die plate fitting in said core box and carried by said rod, and
5 means in the base to support said rod and move the same vertically to eject the die plate.

In testimony whereof, I have signed my name to this specification, in the presence of two subscribing witnesses.

WILLIAM H. FORD.
